CLAIM

The ornamental design for a jewelry bail, as shown and described.

DESCRIPTION

FIG. 1 is a top plan view of a jewelry bail, showing my new design;

FIG. 2 is a front perspective view;

FIG. 3 is a front elevational view;

FIG. 4 is a side elevational view, the opposite side view being a mirror image thereof, it being understood that this view represents all embodiments;

FIG. 5 is a rear elevational view;

FIG. 6 is a bottom plan view;

FIG. 7 is a rear perspective view;

FIG. 8 is a top plan view of a jewelry bail, showing a second embodiment of my new design;

FIG. 9 is a front perspective view of the embodiment of FIG. 8.

FIG. 10 is a front elevational view of the embodiment of FIG. 8.

FIG. 11 is a rear elevational view of the embodiment of FIG. 8.

FIG. 12 is a bottom plan view of the embodiment of FIG. 8.

FIG. 13 is a rear perspective view of the embodiment of FIG. 8.

FIG. 14 is a top plan view of a jewelry bail, showing a third embodiment of my new design;

FIG. 15 is a front perspective view of the embodiment of FIG. 14.

FIG. 16 is a front elevational view of the embodiment of FIG. 14.

FIG. 17 is a rear elevational view of the embodiment of FIG. 14.

FIG. 18 is a bottom plan view of the embodiment of FIG. 14; and,

FIG. 19 is a rear perspective view of the embodiment of FIG. 14.
